US0D1078361S

(12) **United States Design Patent** (10) Patent No.: **US D1,078,361 S**
(45) Date of Patent: ** Jun. 10, 2025

(54) **INDUCTION RANGE**

(71) Applicant: **LG ELECTRONICS INC.**, Seoul (KR)
(72) Inventors: **Jisoo Lim**, Seoul (KR); **Miyoung Kim**, Seoul (KR); **Wonjun Lee**, Seoul (KR)
(73) Assignee: **LG ELECTRONICS INC.**, Seoul (KR)

(**) Term: **15 Years**

(21) Appl. No.: **35/520,969**

(22) Filed: **May 18, 2023**

(80) **Hague Agreement Data**

Int. Filing Date: **May 18, 2023**
Int. Reg. No.: **DM/229418**
Int. Reg. Date: **May 18, 2023**
Int. Reg. Pub. Date: **May 24, 2024**

(30) **Foreign Application Priority Data**

Dec. 15, 2022 (KR) 30-2022-0052872
(51) LOC (15) Cl. **07-02**
(52) U.S. Cl. **USPC** **D7/346**

(57) **CLAIM**

The ornamental design for an induction range as shown and described.

DESCRIPTION

1. Induction range
- 1.1 : Perspective
- 1.2 : Front
- 1.3 : Back
- 1.4 : Left
- 1.5 : Top
- 1.6 : Reference

The omitted right view is a mirror image of the left view and the omitted bottom view is a mirror image of the top view; the broken lines shown in reproductions 1.1 to 1.5 depict portions of the induction range that form no part of the claimed design; reproduction 1.6 shows a state in use of the

(Continued)

claimed design, wherein all other broken lines are for environment purpose only and form no part thereof.

1 Claim, 6 Drawing Sheets
